UNITED STATES PATENT OFFICE.

WILLIAM E. KORNBAUM, OF HANOVER, KANSAS.

DESIGN FOR A CASING FOR MILK-COOLERS.

SPECIFICATION forming part of Design No. 26,992, dated April 27, 1897.

Application filed February 12, 1897. Serial No. 623,193. Term of patent 7 years.

To all whom it may concern:

Be it known that I, WILLIAM E. KORNBAUM, a citizen of the United States, residing at Hanover, in the county of Washington and 5 State of Kansas, have invented and produced a new and original Design for a Casing for Milk-Coolers; and I do hereby the following to be a full, clear, and exact description of the same, reference being had to the accompanying drawings, forming a part thereof.

My invention relates to a design for the casing for a milk cooler or creamer.

It relates to the entire configuration of the cooler-casing.

15 My invention relates particularly to the design for the casing for a milk-cooler, as illustrated in the accompanying drawings, in which—

Figure 1 is a perspective view of a milk-cooler casing embodying my design. Fig. 2 is a top plan view of the same.

The leading features of my design appear in the following description.

1 represents a rectangular casing having 20 rectangular parallel sides and ends. At one end appears a chute 2 near its top, and below this is a projecting tube 3. The top 4 of the

casing is likewise rectangular, as shown, and is formed with a depression or recess 5, having a plane bottom 6, arranged parallel with the 30 top. In one corner of the bottom appears an orifice 7, and in the opposite corner of the same side appears another orifice 8. A pair of inverted-V-shaped ribs 9 and 10 project upward from the said bottom at the opposite 35 ends of the bottom. These ribs are parallel with the ends and parallel with each other. A third V-shaped rib 12 is located midway between the two former, as shown.

13 and 14 represent circular tubes extending 40 upward through the plane of the bottom 6.

Having thus fully described my invention, what I claim as new and useful, and desire to secure by Letters Patent of the United States, is—

The design for the casing for a milk-cooler substantially as herein shown and described.

In testimony whereof I affix my signature in presence of two witnesses.

WILLIAM E. KORNBAUM.
